FIG. 3

Fig. 1 is a perspective view of a floor polisher showing my new design with the cord broken away in part to indicate indeterminate length;

Fig. 2 is an enlarged fragmentary front elevational view thereof with portions broken away for convenience of illustration;

Fig. 3 is an enlarged fragmentary rear perspective view of Fig. 2;

Fig. 4 is an enlarged side elevational view of the floor polishing housing.

The dominant features of my design reside in the portions shown in full lines.

I claim:

The ornamental design for a floor polisher, as shown and described.
